UNITED STATES PATENT OFFICE.

HARRY C. UMIPLEBY, OF ANGELICA, NEW YORK.

AUTOMATIC LATCH.

No. 799,115.

Specification of Letters Patent.

Patented Sept. 12, 1905.

Application filed March 15, 1905. Serial No. 250,158.

To all whom it may concern:

Be it known that I, HARRY C. UMIPLEBY, a citizen of the United States, residing at Angelica, in the county of Allegany and State of New York, have invented new and useful Improvements in Automatic Latches, of which the following is a specification.

My invention is an automatic latch, and more particularly a device of this kind to be used in connection with an animal-trap.

The object of the invention is to provide a simple and efficient device of this kind; and to this end it consists in certain novel features of construction, hereinafter described and claimed.

In the accompanying drawings, Figure 1 is a side elevation of the trap. Fig. 2 is a longitudinal section. Fig. 3 is a front end view with the door closed. Fig. 4 is a sectional detail showing the U-shaped tripper referred to hereinafter.

Referring specifically to the drawings, the cage comprises a floor 5, open sides 6, a top 7, and its rear end is closed by a door 8. The front end of the cage has a door 9, which is hinged at the top of the cage and has a spring 10 for closing it. The door is held open by a detent-rod 11, sliding on top of the cage in a guide 12, the outer end of the rod entering a socket in a block 13 on the door. The inner end of the rod is connected to one arm of a bell-crank lever 14, pivoted at the top of the cage. The other arm of the lever is connected by a rod 15 with a tilting plate 16 on the floor of the cage and working on pivots 17. Any suitable means for holding the bait can be employed, as a hook 18, depending from the top of the cage. The bait-holder will be placed close to the plate 16, so that the bait cannot be reached without the animal stepping on the plate. When this is done, the connections described cause the rod 11 to be withdrawn from the socket in the block 13, thereby permitting the spring 10 to close the door 9.

The means for holding the door closed com-

prise a spring-bolt 19, which works in a casing 20, containing a spring 21. A bracket 22 is secured to the door-casing 22^a, in which bracket a U-shaped tripper 23 is slidably supported. The free ends 24 and 25, respectively, of the tripper extend through the door-casing to the outside of the cage. The end 24 enters a notch made in the bolt 19 to hold it retracted. When the door swings down to close, it strikes the end 25 and slides the tripper rearwardly, which removes its end 24 from the notch in the bolt and releases the latter, which then shoots forward behind the door, thereby securely holding it closed. The door is cut away on one side, as at 26, to enable it to pass the bolt and its casing as it swings downwardly to close. The door also has holes 27, in which the heads 28 of the screws 29, whereby the bracket 22 is secured, fit. This enables the door to shut tightly.

Having thus described my invention, what is claimed as new, and desired to be secured by Letters Patent, is—

1. The combination with a door, of a sliding bolt for holding the door closed, and a U-shaped tripper slidably supported adjacent the door-opening, one of the free ends of the tripper engaging the bolt for holding it retracted and the other free end being engageable by the door for releasing the bolt.

2. The combination with a door, of a sliding bolt extensible behind the door for holding it closed, and having a notch, and a U-shaped tripper slidably supported on the door-casing, one of the free ends of the tripper entering the notch in the bolt to hold it retracted, and the other free end being engageable by the door for releasing the bolt.

In testimony whereof I have signed my name to this specification in the presence of two subscribing witnesses.

HARRY C. UMIPLEBY.
